UNITED STATES PATENT OFFICE

134,135

DESIGN FOR A COMBINED LAPEL WATCH AND REFLECTOR BUTTON

Alfred Benjamin Shawl, New York, N. Y.

Application January 27, 1942, Serial No. 105,458

Term of patent 3½ years

To all whom it may concern:

Be it known that I, Alfred Benjamin Shawl, a native of Poland, stateless, residing at 10 West 47th Street, New York, in the county of New York and State of New York, have invented a new, original, and ornamental Design for a Combined Lapel Watch and Reflector Button, of which the following is a specification, reference being had to the accompanying drawing, forming part thereof.

In the drawing:

Fig. 1 is a front view of a combined lapel watch and reflector button with the watch dial in front;

Fig. 2 is a side view of the design;

Fig. 3 is a view of the disclosure in Fig. 1 with the button turned upward now showing the reflector in front.

I claim:

The ornamental design for a combined lapel watch and reflector button, as shown.

ALFRED BENJAMIN SHAWL.
